UNITED STATES PATENT OFFICE

OLLIE S. LETZKUS, OF PITTSBURGH, PENNSYLVANIA

DESIGN FOR A SHADOWGRAPHIC TOKEN

Application filed November 25, 1930. Serial No. 37,786. Term of patent 14 years.

To all whom it may concern:

Be it known that I, OLLIE S. LETZKUS, a citizen of the United States, residing at Pittsburgh, in the county of Allegheny and State of Pennsylvania, have invented a new, original, and ornamental Design for a Shadowgraphic Token, of which the following is a specification, reference being had to the accompanying drawing, forming part thereof.

In the drawing:

Fig. 1 is a plan view of a token showing my new design.

Fig. 2 is a bottom view thereof.

The token is formed to cast a shadow representing the face of Christ, and is provided at its lower edge with a plurality of pointed projections having the configuration of the shadow of His beard, and formed integral with the token is a bail spaced from the top of the token by a crescent-shaped slit which produces a pronounced halo effect.

I claim:

The ornamental design for a shadowgraphic token, as shown and described.

OLLIE S. LETZKUS.
